UNITED STATES PATENT OFFICE

2,374,757

TWO-STAGE WATER HEATER

Ernst R. Koppel, Milwaukee, Wis., assignor to
 A. O. Smith Corporation, Milwaukee, Wis., a
 corporation of New York

Application August 21, 1943, Serial No. 499,488

13 Claims. (Cl. 122—17)

This invention relates to a two-stage water heater.

The principal object of the invention is to provide the heater storage tank with a booster section for supplying relatively small quantities of very hot water.

Another object is to provide a heater with inter-connected heater storage chambers, one of which is adapted to store water at a substantially higher temperature than the other.

Another object is to provide such a heater in which the water in the hotter chamber may be by-passed to the other chamber to aid in heating the water therein.

Other objects and advantages will appear hereinafter.

The accompanying drawing illustrates an embodiment of the invention and the views thereof are as follows:

Figure 1 is a vertical central section through a heater; and

Fig. 2 is a transverse horizontal section taken on line 2—2 of Fig. 1.

The water heater comprises in general an upright cylindrical water storage tank 1 with a gas burner 2 or other suitable heating means beneath the tank and a flue 3, preferably central of the tank for conducting the products of combustion from the burner to a chimney.

The tank 1 may be of the type set forth in United States Patent No. 2,263,021 to Uecker, in which the cylindrical walls and head are of ordinary steel and are protected from corrosion by a lining of ceramic enamel or the like. The flue 3 is welded to the heads of the tank and should be constructed of suitable non-corrodible material or be suitably protected by a coating of such material.

A cold water inlet 4 is provided in the side wall near the bottom of the tank, and a hot water outlet 5 is similarly provided near the top of the tank. A thermostatic control valve 6 is secured to the side of the tank 1 at a suitable height to be responsive to the temperature of the water in tank 1 at that height, and is connected to the gas supply pipe 7 for burner 2 to control operation of the latter in a manner to maintain the water in tank 1 at a given predetermined temperature.

In carrying out the invention an auxiliary storage chamber 8 is provided to receive heat directly from the flue 3 and to store water at a higher temperature than that in the tank 1. The chamber 8 may be provided as a tank in the flue, but preferably it surrounds the flue and comprises a cylindrical wall 9 concentric with the flue

and of substantially smaller diameter than that of the shell of tank 1. The upper and lower ends of cylinder 9 are closed by head plates 10 which are secured to the flue 3 and serve to support the cylinder thereon. The wall 9 and heads 10 of chamber 8 are preferably constructed of heat insulating material.

A series of holes 11 are provided in wall 9 near the bottom of chamber 8 for the inlet of water 10 from tank 1 to chamber 8. An outlet pipe 12 is connected to the upper end of chamber 8 for the purpose of drawing off hot water therefrom. A thermostatically controlled by-pass 13 is provided in the upper end of chamber 8 to discharge water into tank 1 when the water in chamber 8 exceeds a predetermined temperature.

It is contemplated that the valve 13 will be set to pass water when the water in chamber 8 reaches a temperature of about 170° to 180° F., 20 whereas the thermostatically controlled valve 6 functions to maintain the water in tank 1 at a temperature between 125° and 140° F.

In operation the water in chamber 8 receives most of the heat from the burner 2, and when it reaches the temperature for which valve 13 is set the valve opens and the water circulates by convection into tank 1 and downwardly therein, cooler water entering chamber 8 through holes 11 to replace it. Additional heat is passed directly from burner 2 to tank 1 through the bottom of tank 1. When the water in tank 1 at the level of the thermostat 6' reaches the temperature for which the thermostat is set, valve 6 shuts off the supply of gas to burner 2. The thermostat 6' again operates valve 6 to start the burner 2 when the water in tank 1 cools to a predetermined lower setting of the thermostat.

When it is desired to draw off very hot water, this is done through pipe 12 connecting with the upper end of chamber 8. When it is desired to draw off moderately hot water, this is done through outlet 5 at the upper end of tank 1. The drawing off of water through outlet 5 does not appreciably lower the temperature of the water in chamber 8, particularly since thermostat 6' will start burner 2 operating after a comparatively small quantity of water has been drawn. Nor does the drawing off of water through pipe 12 lower the temperature of the water in tank 1, 40 except as it may stop the by-passing of water through valve 13 temporarily, and except for the fact that the incoming cold water, replacing the quantity drawn from pipe 12, may trip thermostat 6' and start burner 2 if an appreciable quantity 50 of water is drawn.

If the heater should be on "standby" for any substantial length of time, the temperature between chamber 8 and tank 1 will level out due to heat transfer through wall 3. However, upon starting of burner 2, most of the heat will be concentrated upon the contents of chamber 8, and this comparatively small quantity of water will be reheated to a higher temperature in a very short time.

The invention may have various embodiments within the scope of the accompanying claims.

I claim:

1. In a water heater, a water storage tank having a passage for hot gases therethrough to heat the same, a secondary chamber in said tank and surrounding said passage to receive heat directly from the gases in said passage, a common source of water supply for said tank and said chamber, and a passage having a thermally controlled valve therein for the flow of heated water from said secondary chamber to said tank.

2. In a water heater, a water storage tank having a passage for hot gases therethrough to heat the same, a secondary chamber receiving heat directly from the gases in said passage, a common source of water supply for said tank and said chamber, a thermally controlled passage for the flow of heated water from said secondary chamber to said tank, and means to withdraw heated water from said tank and from said chamber independently.

3. In a water heater, a water storage tank having a passage for hot gases therethrough to heat the same, a secondary chamber receiving heat directly from the gases in said passage, a common source of water supply for said tank and said chamber, a thermally controlled passage for the flow of heated water from said secondary chamber to said tank, means to withdraw heated water from said tank and from said chamber independently, and means to regulate the supply of hot gases to said passage in response to the temperature of the water in said tank.

4. In a water heater, a water storage tank having a passage for hot gases therethrough to heat the same, a secondary chamber receiving heat directly from the gases in said passage, a common source of water supply for said tank and said chamber, a thermally controlled passage for the flow of heated water from said secondary chamber to said tank, means to withdraw heated water from said tank and from said chamber independently, and means to regulate the supply of hot gases to said passage in response to the temperature of the water in said tank, said last named means including a thermostat set at a lower temperature than that at which said thermally controlled passage opens to maintain a substantial temperature differential between the water in said tank and the water in said chamber.

5. In a water storage heater, an upright substantially cylindrical tank with a heating burner beneath, a flue for conducting hot gases from said burner vertically upward through said tank, a secondary chamber in direct contact with the hot gases in said flue for heating an enclosed quantity of water, means to admit water to said chamber from the lower end of said tank, means to admit water to the upper end of said tank from the upper end of said chamber, and means to maintain said last named means closed when the water in said chamber is below a predetermined temperature.

6. In a water storage heater, an upright substantially cylindrical tank with a heating burner

beneath, a flue for conducting hot gases from said burner vertically upward through said tank, a secondary chamber in direct contact with the hot gases in said flue for heating an enclosed quantity of water, means to admit water to said chamber from the lower end of said tank, means to admit water to the upper end of said tank from the upper end of said chamber, means to maintain said last named means closed when the water in said chamber is below a predetermined temperature, and means to withdraw heated water from said tank and from said chamber selectively.

7. In a water storage heater, an upright substantially cylindrical tank with a heating burner beneath, a flue for conducting hot gases from said burner vertically upward through said tank, a secondary chamber in direct contact with the hot gases in said flue for heating an enclosed quantity of water, means to admit water to said chamber from the lower end of said tank, means to admit water to the upper end of said tank from the upper end of said chamber, means to maintain said last named means closed when the water in said chamber is below a predetermined temperature, and thermostatic means for controlling said burner in response to the temperature of the water in said tank.

8. In a water storage heater, an upright substantially cylindrical tank with a heating burner beneath, a flue for conducting hot gases from said burner vertically upward through said tank, a secondary chamber in direct contact with the hot gases in said flue for heating an enclosed quantity of water, means to admit water to said chamber from the lower end of said tank, means to admit water to the upper end of said tank from the upper end of said chamber, means to maintain said last named means closed when the water in said chamber is below a predetermined temperature, thermostatic means for controlling said burner in response to the temperature of the water in said tank, and means to withdraw heated water from said tank and from said chamber, said last named thermostatic means being set to maintain a substantial temperature differential between the water in said tank and chamber.

9. In a water heater, an upright substantially cylindrical tank with a heating burner beneath, a flue extending upward through said tank for conducting hot gases from said burner, a secondary heating chamber adjacent to said flue and having its bottom in direct communication with the tank at the bottom of the latter and its top adapted to communicate with the top of the tank to provide for circulation of water between the two by convection, an outlet connection for heated water at the upper end of the tank, and a separate outlet for heated water directly from the upper end of said chamber.

10. In a water heater, an upright substantially cylindrical tank with a heating burner beneath, a flue extending axially upward for conducting hot gases from said burner, a secondary heating chamber adjacent to said flue and being in direct communication with the tank at its bottom, an outlet connection for heated water at the upper end of the tank, a similar outlet for heated water at the upper end of said chamber, and a thermostatically controlled valve in a passage between the upper ends of the chamber and tank to effect convection currents of heated water between the chamber and tank when the

water in said chamber has reached a predetermined temperature.

11. In a water heater, an upright substantially cylindrical tank with a heating burner beneath, a flue extending axially upward through said tank for conducting hot gases from said burner, a secondary heating chamber surrounding said flue and being in direct communication with the tank at its bottom, an outlet connection for heated water at the upper end of the tank, a similar outlet for heated water at the upper end of said chamber, a thermostatically controlled valve in a passage between the upper ends of the chamber and tank to effect convection currents of heated water between the chamber and tank when the water in said chamber has reached a predetermined temperature, and a thermostatically controlled valve for supplying fuel to said burner to maintain the temperature of the water in said tank between certain limits.

12. In a water heater, an upright substantially cylindrical tank with a heating burner beneath, a flue extending axially upward through said tank for conducting hot gases from said

burner, a secondary heating chamber adjacent to said flue for receiving heat directly therefrom and being in direct communication with the tank at its bottom, an outlet connection for heated water at the upper end of the tank, a separate outlet for heated water at the upper end of said chamber, and a restricted passage for the flow of heated water from said chamber to said tank by convection.

13. In a water heater, a plurality of chambers receiving heat from the same source and water from the same source, one of said chambers being disposed to receive more heat from said source than the other, intercommunicating means between said chambers for establishing a convectional flow of heated water from said more highly heated chamber to another when the water in said first chamber exceeds a given temperature, and means for preventing said convectional flow of water unless the water in said more highly heated chamber is at a temperature substantially above the temperature of the water in said other chamber.
